DISPLACEMENT PUMP

Roy R. Wight, Wichita Falls, Tex., assignor to
The Texas Company, New York, N. Y., a cor-
poration of Delaware

Application January 2, 1935, Serial No. 20

8 Claims. (Cl. 103—234)

This invention relates to new and useful im-
provements in displacement pumps.

The object of this invention is to obtain a simple
compact displacement pump which will be en-
tirely automatic in its operation after it is once
5 adjusted.

A further object of this invention is the con-
struction of a displacement pump for inter-
mittent operation in gas lift oil wells which will
10 be controlled by the static pressure of oil in the
well.

Another object of this invention is the con-
struction of a displacement pump which will be
economical in its operation and which when used
15 in gas lift oil wells will use a minimum of gas
in raising the oil.

In carrying out this invention an eduction tube
is suspended inside the well casing and a piston
chamber is secured to the lower end of the eduction
20 tube. A piston operating in this chamber is
normally maintained in a predetermined position
by mechanical means or by low pressure gas
or other fluid but will be moved from this position
25 by the weight of the column of oil in the
eduction tube when this column reaches a pre-
determined height. The piston is attached to a
sleeve valve which in turn controls the admission
30 to the well of the high pressure gas or other fluid
which is used to carry the oil to the surface.
Thus, with the piston in its normal position the
high pressure gas ports are maintained in a closed
35 position but when the oil seeping into the eduction
tube has reached a predetermined height the
piston is carried out of its normal position and
high pressure gas admitted to the tubing carries
the column of oil in the eduction tube to the sur-
face.

The pump forming the subject of this applica-
40 tion is, of course, not applicable to oil well use
only but may be used wherever a displacement
pump is suitable for the work in hand.

The invention will be more readily understood
45 from a reading of the following specification and
by reference to the accompanying drawing in
which an example of the invention is shown and
described.

Figure 1 is a vertical sectional view of a dis-
placement pump, constructed in accordance with
50 my invention, in which the piston is maintained in
its normal position by low pressure gas supplied
thru a small string of tubing.

Figure 2 shows a displacement pump in which
55 low pressure gas is supplied to the underside
of the piston from a string of tubing surrounding
the eduction tube.

Figure 3 shows a displacement pump in which
the piston is maintained in its normal position by
a spring or other mechanical means.

The same numerical designation for corre-
sponding parts is used throughout the specifica- 5
tion and the drawing.

In Figure 1 the numeral 10 designates the well
casing. The eduction tube 11 is suspended from
the surface inside of the casing and a cylindrical
chamber 12 is securely threaded to the lower end 10
of the eduction tube and is supported thereby.

This chamber is designed to carry a packer 13
which engages the outer chamber wall and the
inner casing wall and effectively cuts off the well
from the upper part of the casing. 15

The base of the chamber is also threaded and
carries a section of pipe 14 which has perforations 15
thru which the oil in the well may enter.

The interior of the cylindrical chamber ac-
commodates a piston 16 which is formed integral 20
with or may be attached to a tubular sleeve valve
17 which controls the high pressure gas ports 18
in the eduction tube. This sleeve valve carries
a check valve 19 at its lower extremity and con-
tains ports 20 opening into the upper piston 25
chamber 21.

Near the base of the lower piston chamber 22
an opening 23 is formed into which a pipe 24 is
threaded, thru which low pressure gas may be
passed to the lower piston chamber. 30

In order that the oil and gas in the well will
not seep into chamber 22 a packing ring 25 may
be placed between the inner wall of the base of
the cylindrical chamber and the exterior of the
sleeve valve. This packing may be held in place 35
by a collar 26 or by some other suitable means.

Figure 2 illustrates a modification of Figure 1
in which the low pressure gas is passed to the
lower piston chamber, not by a small pipe 24
but thru a pipe 27 which surrounds the eduction 40
tube and which is securely threaded to a flange on
the piston chamber. From tube 27 the low pres-
sure gas is passed to the lower piston chamber 22
thru a passage 28 in the wall of the piston cham-
ber. The high pressure ports 18 in the eduction 45
tube and 29 in the tube surrounding it are
connected in this instance by small pipes 30.

As indicated in Figure 2, packing 13 may be
supported from the wall of the tube suspended
from the piston chamber instead of from the walls 50
of the piston chamber.

Figure 3 corresponds almost exactly with Fig-
ure 1 except that a spring 31 of predetermined
55 pressure value is placed in the lower piston cham-

ber 22 and there is, therefore, no low pressure gas tubing or entrance therefor.

Having described the general design of the invention, the operation of the displacement pump 5 will now be disclosed.

Referring first to Figure 1, it will be noted that as the oil rises in the well it will flow into tube 14 thru holes 15 and will gradually rise thru check valve 19 into the interior of the cylindrical sleeve valve and eventually into eduction tube 11.

Under normal conditions a gas of a predetermined low pressure is constantly fed from the surface thru tube 24 and inlet 23 into the lower piston chamber 22 and this gas acting on the 10 underside of piston 16 maintains the sleeve valve in a position such that inlet ports 18 are closed.

The oil in the eduction tube and sleeve valve is, however, permitted to pass thru ports 20 into the upper piston chamber 21 and so exerts pressure 15 on the upper surface of piston 16.

When the oil in the eduction tube has risen to a predetermined height the static pressure of this column will move the piston in a downwardly direction against the force of the low pressure 20 gas and ports 18 will be opened as the sleeve valve is moved in a downwardly direction.

High pressure gas is at all times being forced 25 from the surface into the area between the casing 10 and eduction tube 11 and as soon as ports 18 are opened the gas blows into the eduction tube and raises the column of oil to the surface.

While the pressure within the eduction tube is temporarily raised by the high pressure gas it again drops as the oil is forced out of the tubing 30 at the surface and as the static pressure on top of the piston is decreased the low pressure gas exerts sufficient force to push the piston up and the sleeve valve consequently closes ports 18 shutting off the flow of high pressure gas.

40 This cycle is repeated whenever the column of oil in the eduction tube reaches a height sufficient to counterbalance the force of the low pressure gas, and once the desired pressure on the underside of the piston has been determined and the flow of low pressure gas regulated accordingly, the pump becomes automatic and requires no further attention.

50 The details of the surface equipment do not form a part of this invention and will consequently not be described. It will, however, be obvious, for instance, that there must be a relief valve on the low pressure gas line to take care of the compression of this gas on the down stroke of the piston.

55 The operation of the pump illustrated in Figure 2 is identical with that shown in Figure 1. The low pressure gas, as previously pointed out, being passed to the lower piston chamber 22 thru the space between eduction pipe 11 and the second string of tubing 27 and from there thru passage 28 to chamber 22.

60 The operation of the pump shown in Figure 3 differs from the other two pumps in that the piston is maintained in its normal position by mechanical means rather than by low pressure gas. While a simple coil spring has been illustrated, other suitable mechanical means may obviously be substituted therefor. In this connection, it is to be noted that the selected mechanical means must have a predetermined pressure value so that a column of oil of the desired height will effectively depress the piston and allow the high pressure gas to enter the eduction 65 tube.

It will be seen from the foregoing description that the construction of this pump is extremely simple and compact and that there is little or nothing to get out of order.

It will also appear that there is little loss in 5 low pressure gas and a minimum loss of high pressure gas for when sufficient gas has been admitted to the eduction tube to carry the oil to the surface the high pressure gas supply is cut off.

Obviously many modifications and variations 10 of the invention, as hereinbefore set forth, may be made without departing from the spirit and scope thereof, and therefore only such limitations should be imposed as are indicated in the appended claims.

15 I claim:

1. In a displacement pump an outer casing, a centrally disposed tube, a port located in said tube, a cylindrical chamber connected with said tube, a piston adapted to operate in said chamber, means controlled by the piston for controlling said port, an aperture in said control means giving access to the upper surface of the piston, means for maintaining a predetermined pressure on the lower surface of the piston and a check 20 valve, seated in the lower end of said control means.

2. The combination with a well casing of a centrally disposed tube, a port located in said tube, a chamber suspended from said tube, a 30 packer engaging the outer walls of said chamber and the casing wall, a piston in the form of a hollow cylinder located in said chamber, a cylindrical sleeve secured to the inner surface of said piston and adapted to control the port in said first tube, an aperture in said sleeve giving access to the upper surface of the piston, a second tube disposed between the first tube and the casing and leading into the lowest portion of the 35 piston chamber.

40 3. The combination with a well casing of a centrally disposed tube, a port located in said tube, a chamber suspended from said tube, a packer engaging the outer wall of said chamber and the casing wall, a piston in the form of a hollow cylinder located in said chamber, a cylindrical sleeve secured to the inner surface of said piston and adapted to control the port in said first tube, an aperture in said sleeve giving access to the upper surface of said piston and mechanical 45 means for maintaining the piston in a predetermined normal position.

4. The combination with a well casing of two tubes disposed one within the other, a tubular port connecting the space between the casing and the outer tube with the interior of the inner tube, a chamber suspended from said tubes, a piston in the form of a hollow cylinder located in said chamber, a cylindrical sleeve secured to the inner surface of said piston and adapted to control said port, an aperture in said sleeve giving access to the upper surface of the piston, a passage leading from the space between said inner and outer tubes into the lower portion of the 55 piston chamber, a tube suspended from said piston chamber and a packer engaging the outer wall of said last mentioned tube and the casing wall.

5. In a well pumping apparatus operated by 60 the displacement of liquid by fluid under pressure a casing, a centrally disposed eduction tube having gas ports located in its walls adjacent to its lower ends, a piston chamber suspended from said eduction tube and having openings at both 65 70 75

ends, a packer engaging the outer wall of said chamber and the inner casing wall and adapted to prevent high pressure gas from passing from the space between the casing and eduction tube into the well, a piston in the form of a hollow cylinder adapted to operate in said chamber, a cylindrical sleeve of greater length than the piston chamber secured to the inner surface of said piston and extending thru the opening in the piston chamber and adapted to close the gas ports in the eduction tube when the piston is in its upper position, a check valve located in the lower end of said sleeve adapted to permit the liquid being pumped to flow into the sleeve, apertures in the sleeve adapted to admit such liquids to the upper surface of the piston, a second tube disposed between the casing and the eduction tube and connected with the piston chamber which is adapted to admit low pressure gas to the lower surface of the piston.

6. In a well pumping apparatus operated by the displacement of liquid by fluid under pressure a casing, a centrally disposed eduction tube having gas ports located in its walls adjacent to its lower ends, a piston chamber suspended from said eduction tube and having openings at both ends, a packer engaging the outer wall of said chamber and the inner casing wall and adapted to prevent high pressure gas from passing from the space between the casing and eduction tube into the well, a piston in the form of a hollow cylinder adapted to operate in said chamber, a cylindrical sleeve of greater length than the piston chamber secured to the inner surface of said piston and extending thru the opening in the piston chamber and adapted to close the gas ports in the eduction tube when the piston is in its upper position, a check valve located in the lower end of said sleeve adapted to permit the liquid being pumped to flow into the sleeve, apertures in the sleeve adapted to admit such liquids to the upper surface of the piston, a spring mounted in the piston chamber below the piston adapted to main-

tain the piston in a predetermined normal position.

7. In a pumping apparatus operated by the displacement of liquid by fluid under pressure an eduction tube, a port in said eduction tube adapted to admit high pressure fluid into the eduction tube, a sleeve valve adapted to control the said port, a piston adapted to control said sleeve valve, means for admitting the liquid to be pumped to the upper surface of the piston, a low pressure fluid source and means for applying such fluid to the lower surface of the piston to maintain the piston in a predetermined normal position.

8. In a well pumping apparatus operated by the displacement of liquid by fluid under pressure a casing, an outer tube disposed within the casing, an eduction tube disposed within said outer tube, a tubular port connecting the space between the casing and the outer tube with the interior of the eduction tube, a piston chamber suspended from said tubes and having openings at both ends, a piston in the form of a hollow cylinder adapted to operate in said chamber, a cylindrical sleeve of greater length than the piston chamber secured to the inner surface of said piston and extending thru the openings in the piston chamber and adapted to close the port in the eduction tube when the piston is in its upper position, a check valve mounted in the lower end of said sleeve adapted to admit the liquid being pumped into the sleeve, apertures in the sleeve adapted to admit such liquid to the upper surface of the piston, a passage in the piston chamber wall connecting the area between said outer tube and the eduction tube with the lowest portion of the piston chamber, a perforated tube suspended from said piston chamber and a packer engaging the outer wall of said last mentioned tube and the casing wall to prevent high pressure gas from passing from the space between the casing and the centrally disposed tubing into the well.

ROY R. WIGHT.
